(57) **CLAIM**

The ornamental design for a shredding chamber screen, as shown and described.

DESCRIPTION

FIG. 1 is a left front perspective view of a shredding chamber screen, showing my new design;

FIG. 2 is a top plan view, thereof;

FIG. 3 is a front elevational view, thereof;

FIG. 4 is a bottom plan view, thereof;

FIG. 5 is a rear elevational view, thereof;

FIG. 6 is a left-side elevational view, the right-side elevational view being substantially a mirror image, thereof; and, FIG. 7 is a layout view, showing the hole pattern, thereof. The broken line showing of environment in FIG. 1 is for illustrative purposes only and forms no part of the claimed design.
